(57) **CLAIM**

The ornamental design for a hat as shown and described.

DESCRIPTION

1. Hat

1.1 : Front

1.2 : Back

1.3 : Bottom

1.4 : Top

1.5 : Left

1.6 : Right

The design is a hybrid wide-brimmed hat that combines the elegance of a fedora with the urban and sporty style of a baseball cap; the top is a baseball cap without its visor, which perfectly integrates with and adheres to the sophisticated silhouette of the fedora; the circular, rigid brim measures between 8 and 8.5 cm; a 3D front embroidery and a custom buckle band complete the design, merging the two styles (urban and classic) into one.
